Attn:

MILO WEBB, OF CHENANGO FORKS, NEW YORK.

Letters Patent No. 84,451, dated November 24, 1868.

IMPROVEMENT IN MECHANICAL MOVEMENT.

The Schedule referred to in these Letters Patent and making part of the same.

To all whom it may concern:

Be it known that I, MILO WEBB, of Chenango Forks, in the county of Broome, and State of New York, have invented a certain new and useful Improvement in Churn-Power, or power for other purposes; and do hereby declare that the following is a full, clear, and exact description thereof, reference being had to the accompanying drawings, and to the letters of reference marked thereon.

The nature of my invention consists in a simple and effective device for obtaining power by means of springs or weights, which can be used to operate a churn, or for a variety of purposes.

In order to enable others skilled in the art to which my invention appertains, to make and use the same, I will now proceed to describe its construction and operation, referring to the annexed drawings, which form a part of this specification, and in which—

Figure 1 is a front elevation;

Figure 2, a side elevation;

Figure 3, a front view of the escapement-bar and dogs; and

Figure 4, a side view of the driving-wheel, showing its attachment to the main shaft or cylinder.

A represents a frame, of suitable material and dimensions, in the upper part of which a shaft, B, has its bearings.

On this shaft, a cylinder or roller, C, is firmly secured, which cylinder has flanges on its ends, to prevent the rope or chain, which is to be wound on the same, from slipping off.

A chain, D, is attached to the side of the cylinder C, near one end, which chain is wound around a cylinder, E, secured to a shaft in the lower part of the frame.

A spring, H, is also secured to the said shaft and to the frame, in such a manner that, when the shaft B is turned, unwinding the chain from the cylinder E, and winding it on the cylinder C, the spring is wound up, and then, by its own force, unwinds the chain from the cylinder C, and rewinds it on to the cylinder E.

At one end of the cylinder C, a cog-wheel, F, is placed on the shaft B, and connected with the cylinder by a pawl or dog, a, which works in notches on the flange at that end of the cylinder, as shown in fig. 4.

The pawl a is held in position by means of a spring, b, secured to the inner side of the wheel F.

The cog-wheel F gears into a pinion, d, on the shaft G, which latter is placed below the cylinder C, and has its bearings in the sides of the frame A.

On the shaft G is firmly secured an escapement-wheel, I, which is cut with a series of notches on both sides, around its entire outer edge, as shown in fig. 1.

On a cross-bar, on the front side of the frame A, is a plate or bar, e, firmly secured, the ends of which bar are bent downward, and in these bent ends the shaft i has its bearings.

The rear end of the bar e forms, at the lower end, two ears f, each of which has a small pin, g, extending backward, one on each side of the wheel I.

On the rear end of the shaft i, the escapement-bar h is secured.

At each end of the bar h is a pin, extending to the rear, and on these pins the escapement-dogs o o are pivoted, and the whole so arranged that they work, one on each side of the wheel I, in the notches thereon, and inside of the pins g g.

A small spring, m, is attached to the attachment-bar h, and wound around the pins on the same, and on the inner side of the dogs o o, so that when the escapement-wheel I revolves, it catches the dog on one side, moving that end of the escapement-bar h up until the spring m, on the other side, strikes the ear f, when said dog is thrown out from the wheel. The dog on the other side, in the mean time, being caught on its side of the wheel, carries that end of the bar up, thus alternating, and giving the shaft i a reciprocating motion.

A lever, L, is secured to the shaft i, one end of which lever is connected, by a rod, M, to the balance-wheel N, on the front side of the frame, and to the other end of said lever a rod, O, is pivoted, which, at its lower end, is provided with a churn-dasher, P.

It will be seen that the churn-dasher P acquires a very rapid up-and-down-motion, and that this device can be applied to most any purpose where power is wanted to drive machinery.

The power produced hereby is not exhausted or used up by complicated gearing, everything being simple, and working with ease.

Instead of using the spring H to drive the machinery, weights may be substituted, with equal advantage.

For the purpose of regulating the speed of the machine, and of stopping the same whenever desired, I place a regulator, R, on the side of the frame A. This regulator consists of two spring-bars, connected at the top, and extending downward, one on each side of the shaft, to which the balance-wheel N is secured.

Near the upper end, or at any suitable point, a thumbscrew, S, passes through the said spring-bars, so that, by turning the screw, the bars clasp the balance-wheel shaft the tighter the more the screw is turned, thus regulating the speed or stopping the machine altogether.

Having thus fully described my invention,

What I claim as new, and desire to secure by Letters Patent, is—

The arrangement of the frame A with cylinder C, chain D, cylinder E, spring H, wheels F I, shaft G, dogs o o, bar h, shaft i, spring m, regulator R and its screw S, wheel N, bar L, and rod O, all, with their various parts, constructed and operating substantially as herein set forth.

In testimony that I claim the foregoing, I have hereunto set my hand and seal, this 13th day of August, 1868.

MILO WEBB. [L. S.]
